UNITED STATES PATENT OFFICE.

CHARLES F. STODDARD, OF NEW YORK, N. Y.

PERFORATED NOTE-SHEET FOR AUTOMATIC MUSICAL INSTRUMENTS.

1,257,043.

Specification of Letters Patent. Patented Feb. 19, 1918.

Application filed October 12, 1914. Serial No. 866,218.

To all whom it may concern:

Be it known that I, CHARLES F. STODDARD, a citizen of the United States, and a resident of New York, county and State of New York, have invented an Improvement in Perforated Note-Sheets for Automatic Musical Instruments, of which the following description, in connection with the accompanying drawings, is a specification, like characters on the drawings representing like parts.

This invention relates to prime controllers, such as perforated note sheets, for use upon automatic player pianos and the like. One of the objects of the invention is to improve the playing governed by a note sheet, particularly as regards the tone coloring, and to provide for producing the so-called "singing tone" which characterizes and distinguishes the manual playing of some of the greatest artists.

The character of the invention may be best understood by reference to the accompanying drawing which shows, for purposes of illustration, a fragment of a note sheet having perforations arranged in accordance with one aspect of the invention.

Referring to the drawing, the arrow A indicates the assumed direction of travel of the illustrative note sheet. The perforations illustrated in full lines are those which would have been cut in the sheet according to the practice which generally prevailed in the art prior to this invention and a companion invention disclosed in my earlier Patent No. 1,025,077, dated April 30, 1912. That is to say, the full line perforations of the drawing are assumed to have been laid out by reference to a musical score or a record of an artist's playing, by relatively locating the advance ends of the perforations so as to sound their respective notes in desired musical sequence, and by giving to the perforations relative lengths corresponding to the respective durations indicated upon the score or record. The dotted line prolongations of the full line perforations indicate the extension of said perforations for sustaining their notes in pursuance of this invention; and the dotted line perforations at the left-hand margin of the illustrative sheet indicate pedal operating perforations of unique character and purpose which coöperate with the other perforations and prolongations to produce the ultimate refine-

ment in tonal effect contemplated by the present invention.

The transverse lines m , m' and m^2 indicate lines of division between so-called "pedaled sections", i. e., those sections of the note sheet corresponding respectively to periods during which a damper pedal, according to the score or record, is intended to be depressed to hold all the strings undamped. For example, it is assumed that the score or record from which the illustrative note sheet is made indicates a damper pedal operation by which the dampers are removed from the strings at a point corresponding to the line m , are held off the strings during the period represented by the distance from line m to line m' , and are returned to the strings at a point corresponding to the line m' . Similarly the section m' , m^2 represents approximately a second pedal section.

It is assumed that all of the notes corresponding to the perforations in the section m , m' are in harmony and that they may desirably sound concurrently throughout the section. Therefore the perforation 1 is provided with a prolongation 2 so as to contribute the sounding of the note either from the initial percussion or by sympathetic vibration, throughout the period represented by the perforation 1 plus the prolongation 2. Similarly, the perforation 3 is provided with a prolongation 4. The perforation 5 has a prolongation 6 terminating in proximity to the advance end of a resounding perforation 7 which has a prolongation 8. A perforation 9 is followed by resounding perforation 10 which has a prolongation 11. A perforation 12 has a prolongation 13. A perforation 14, instead of being prolonged, is curtailed, having its rear end located at the point indicated by the arrow 15; and likewise a perforation 16 is curtailed having its rear end located at a point indicated by the arrow 17—these curtailments of perforations having an object presently to be described.

A pedal operating perforation 18 (to govern any suitable form of damper pedal operating mechanism) may be used if desired, as presently described, but its use is not indispensable to the substance of the present invention and therefore the perforation 18 may be disregarded for the time being.

One of the purposes of this invention is to provide for prolonging selected notes from one harmony group into another to improve the tonal effects in the second group by adding thereto the notes so selected to the exclusion of non-selected notes. To suit this object it is assumed that the notes of perforations 3, 7, 12 and 19 if continued into the second pedaled section m' , m^2 would add desirably to the harmony of said second section; and it is also assumed that the notes of perforations 1, 10, 14 and 16, if prolonged into the second section m' , m^2 would produce discord. Therefore, the notes of perforations 3, 7, 12 and 19 are the notes selected to be continued into the second section m' , m^2 , to the exclusion of the so-called non-selected notes of the perforations 1, 10, 14 and 16.

To prolong the selected notes, an auxiliary sustaining means is provided to bridge over the interval or hiatus between the first section m , m' and the second section m' , m^2 , such auxiliary sustaining means being exemplified by a damper pedal operating perforation 20, the advance end of which overlaps the rear ends of the prolonged perforations 3—4, 7—8, 12—13, and also overlaps the rear end of the perforation 19. Thus, although the termination of the perforations 4, 8, 13 and 19 tends to reapply the dampers to their respective strings, the pedal operating perforation 20 comes in operation soon enough to retain said dampers in undamped position so that the appropriate strings are held undamped so long as the perforation 20 continues to operate.

If the prolongation 2 were continued to overlap the advance end of the pedal perforation 20, the note of the perforation 1—2 would also be sustained by the pedal perforation 20; but as already stated the note of said perforation 1—2 would be objectionable if continued into the second section m' , m^2 , and therefore the prolongation 2 is terminated at such a point as to return its damper to its string and arrest vibration thereof before the pedal perforation 20 begins to operate. For instance, the prolongation 2 has its rear end located in front of the advance end of the pedal perforation 20. Similarly, the prolongation 11, corresponding to another non-selected note, is terminated in front of the perforation 20.

As already stated, the full line perforations 14 and 16 have lengths which are assumed to correspond with the indications of the score or record from which the note sheet is made. And if these lengths were preserved, the perforations 14 and 16 would overlap the advance end of the pedal perforation 20 which would therefore prolong the notes of the perforations 14 and 16 into the second pedaled section. It is assumed, however, that the notes of perfora-

tions 14 and 16 would produce discord if so continued and therefore said perforations are curtailed to lengths less than those indicated by the score or record, as by having their rear ends located respectively at the points 15, 17, so that the strings of the perforations 14, 16 will be damped before the pedal perforation 20 begins to act. It is true, of course (when the usual automatic damper pedal operation is employed), that the advance end of the pedal perforation 20 promptly undamps the strings after they have been damped by the rear ends of the perforations 11, 14 and 16; but the termination of said last named perforations will have had the effect of stopping the audible residual vibrations of their strings and will have rendered the strings inert so that during the operation of the pedal perforation 20 said strings will vibrate only sympathetically with, in many cases, more subdued tones.

With the described arrangement, the said prolongations continue their respective notes within the first pedaled section m , m' ; and the pedal perforation 20 cooperating with the perforations of the selected notes continues said notes, to the exclusion of the non-selected notes, into the second pedaled section m' , m^2 .

In the second pedaled section, the perforation 22 resounds the note of perforations 5—6 and 7—8, and the note is further continued by a prolongation 23 terminated in proximity to the advance end of another resounding perforation 24. A perforation 25 plays a new note, which is continued by a prolongation 26. A perforation 27 resounds the note of perforations 12—13, which note is continued by a prolongation 28. Another new note is introduced by a perforation 29 and continued by a prolongation 30; and still another note is introduced by a perforation 31. The pedal perforation 20 is shown for illustration as having a length sufficient to overlap the advance ends of all the perforations 22, 25, 27, 29 and 31, the effect of this being to hold the strings undamped during the sounding of the notes of said perforations so as to produce by the continued vibration of the selected strings a singing background, as it were, upon which to superpose the resounding of certain of the notes and the initial sounding of the new notes—it being the provision of such a singing background which produces some of the beautiful tone effects contemplated by this invention.

The length to be given the pedaled perforation 20, or its equivalent or substitute, is a matter to be determined by selection by one skilled in the art. For example, in some cases it may be desired to utilize in the aggregate tone volume, the general sympathetic vibration of all of the strings which

are undamped by the pedal perforation. In other cases it may be desired to minimize this general sympathetic vibration and, under such circumstances, the length of the 5 perforation 20 might be minimized as will be understood by those skilled in the art.

The arrangement thus far described provides for prolonging selected notes from one section into another so that the coöperation 10 of the described prolongations and the illustrative pedal perforation 20 produces a very desirable approximation of tone continuity. To produce a further refinement, however, and practically perfect said continuity, additional auxiliary sustaining means, exemplified by the pedal perforations 18 and 32, may be provided. The pedal perforation 18 has its advance end located in such position 15 as to maintain the string of the perforation 20 5—6 undamped (in spite of the termination of said perforation), and likewise to hold undamped the string of the perforation 9, so that the resounding of the respective notes by the perforations 7 and 10 shall take place 20 while their strings are still undamped. Thus the perforation 18 bridges over the interval between the rear ends of the perforations 6 and 9 and the advance ends of the perforations 7 and 10 so as to continue the 25 sounding of said strings during or until the resounding.

In like manner the perforation 32 continues the sounding from the prolongation 23 until the resounding by the perforation 24.

The effect of coöperation of the prolongations and described pedal perforations will be appreciated in its ultimate refinement when it is noted that the string corresponding 40 to the perforation 5 is held continuously undamped from the time of the initial percussion by the perforation 5, through the prolongation 6, then by the pedal perforation 18, through the note perforation 7 and 45 its prolongation 8, then by the pedal perforation 20, through the note perforation 22 and its prolongation 23, then by the pedal perforation 32, and finally by the perforation 24. Thus following the initial percus- 50 sion of the note, the string may sound continuously, either by residual or sympathetic vibration, so that its sounding may produce a continuous singing effect which is merely punctuated, so to speak, by the resounding— 55 the repeated percussions—by the perforations 7, 32 and 24. Similarly, the string corresponding to the perforation 12 may be held continuously undamped from the time of initial percussion by the perforation 12 60 throughout the playing and to the rear end of the prolongation 28. It will be obvious to those skilled in the art that arrangements such as those described offer opportunity for producing very beautiful tone effects.

65 It is to be understood that this invention

is not limited to the particular organization and arrangement described above for illustration, since the particular details of construction may be variously changed and the invention may be variously embodied. 70 Furthermore, it is not indispensable that all the features of the invention be used conjointly, since they may be used separately in various combinations and sub-combinations.

Claims—

1. A note sheet for automatic musical instruments comprising a succession of groups of note-sounding perforations; certain of said perforations being prolonged beyond lengths corresponding to the indications of 80 the score or record from which the note sheet is made, to sustain the notes of said prolonged perforations within a group; and auxiliary sustaining perforations coöperating with selected ones of said prolonged 85 perforations to the exclusion of non-selected notes, to continue the notes of said selected perforations from their original group into another group.

2. A note sheet for automatic musical instruments comprising a succession of groups of note-sounding perforations, certain perforations in a group being prolonged beyond lengths corresponding to the indications of 90 the score or record from which the note sheet is made, and certain of said prolongations being longer than others; and auxiliary sustaining perforations coöperating with said longer perforations to the exclusion of the others to continue the notes of 95 said longer perforations from their original group into another group.

3. A note sheet for automatic musical instruments comprising a succession of groups of note-sounding perforations, certain of 100 said perforations being curtailed to lengths less than the lengths indicated by the score or record from which the note sheet is made; and auxiliary sustaining perforations co- 105 operating with non-curtailed note perforations to continue the notes thereof from their original group into another group to the exclusion of the notes of the curtailed perforations.

4. A note sheet for automatic musical instruments comprising a succession of groups of note sounding perforations, certain selected perforations being prolonged to sustain their notes within a group; and auxiliary sustaining perforations for sustaining notes 110 of one group into another.

5. A note sheet for automatic musical instruments comprising a succession of pedaled sections of note-sounding perforations; and an auxiliary sustaining perforation ex- 115 tending from one pedaled section into the next.

6. A note sheet for automatic musical instruments comprising a succession of pedaled sections of note-sounding perforations; 120 125 130

4
an auxiliary sustaining perforation extending from one pedaled section into the next; and certain selected perforations in the first pedaled section being prolonged to coöperate with said auxiliary sustaining perforation.

5 7. A note sheet for automatic musical instruments comprising a succession of pedaled sections of note-sounding perforations; an auxiliary sustaining perforation extending from one pedaled section into the next; and certain perforations of said first pedaled section being curtailed to terminate its note prior to the operation of said auxiliary sustaining perforation.

10 8. A note sheet for automatic musical instruments comprising a succession of groups of note-sounding perforations including

sounding and resounding perforations; and perforations for sustaining selected notes through a plurality of resounding operations comprising prolongations of individual note perforations, auxiliary sustaining perforations for bridging intervals between sounding and resounding notes and auxiliary sustaining perforations for bridging the interval between one group and another. 20 25

In testimony whereof I have signed my name to this specification in the presence of two subscribing witnesses.
